Patented Oct. 13, 1959

186,347

POCKET ASH TRAY

Remigio Persico, Cleveland, Ohio

Application March 28, 1958, Serial No. 50,220

Term of patent 3½ years

(Cl. D85—2)

Fig. 1

Fig. 2

The back of the article is substantially plain and unornamented.

I claim:

The ornamental design for a pocket ash tray, substantially as shown and described.
